DESIGN FOR A WALL BRACKET

Frederick H. Fisher, Syracuse, N. Y., assignor to Syracuse Ornamental Co., Syracuse, N. Y., a copartnership

Application August 7, 1945, Serial No. 121,292

Term of patent 3½ years

(Cl. D33—3)

To all whom it may concern:

Be it known that I, Frederick H. Fisher, a citizen of the United States, residing in Syracuse, in the county of Onondaga and State of New York, have invented a new, original, and ornamental Design for a Wall Bracket, of which the following is a specification, reference being had to the accompanying drawing, forming a part thereof.

Fig. 1 is a bottom front perspective view of a wall bracket showing my new design; and

Fig. 2 is a side top perspective view.

I claim:

The ornamental design for a wall bracket, substantially as shown.

FREDERICK H. FISHER.
